TOBACCO DISPENSER

Max Friedman, High Point, N. C.

Application September 19, 1950, Serial No. 185,575

8 Claims. (Cl. 206—41.1)

1

This invention relates to dispensers and more particularly to a device for dispensing tobacco or other fluent material which may be used for supplying the same to pipes, cigarette paper or to other objects.

The present invention is an improvement over the structure disclosed in my co-pending application, Serial No. 794,635, which has resulted in Patent No. 2,565,808.

Containers for material such as tobacco adapted for carrying on the person have been used heretofore and have generally constituted pouches and the like although receptacles including dispensers have been known heretofore. Among the requirements for a satisfactory container for personal use are that the receptacle be capable of being easily filled and that a suitable charge can be easily ejected as well as that the receptacle be substantially air-tight in order to keep the contents from drying out.

Accordingly it is an object of the present invention to provide a combined container and dispenser for fluent material which is of simple, inexpensive and durable construction, easy to operate and adapted to efficiently dispense materials with a minimum of effort.

A further object of the invention is to provide a combined container and dispenser for fluent material which may be easily filled and the material ejected and which keeps the material substantially air-tight.

Further objects and advantages of the invention will be apparent from the following description taken in conjunction with the accompanying drawings wherein:

Fig. 1 is a plan view of a device according to the invention with the cover partly broken away illustrating its interior, the ejecting mechanism being shown in phantom in discharge position.

Fig. 2, a section at right angles to Fig. 1 illustrating the use of the device;

Fig. 3, a side elevation of the device in closed position; and

Fig. 4, a section on the line 4—4 of Fig. 3.

Briefly stated, the device of the present invention comprises a pair of cup members, each formed of a cylindrical wall and a disk closing such wall at one end of the same. These cup members are fitted together to form a relatively tight container for tobacco or the like and the cup members are provided with diametrically disposed openings which may be brought into registration for dispensing of the tobacco, a combination control plunger and tamper being provided for controlling the discharge and tamping

2

tobacco in the receiving bowl of a smoker's pipe.

With combined reference to the drawings, the device of the present invention comprises a substantially cylindrical and relatively shallow receptacle or container 10, including a bottom 11 and an annular upstanding rim or cylindrical wall 12. Around the base of the wall 12 is located an extended flange 13 provided with a scalloped or notched gripping edge 13' to facilitate the holding of the container and the relative rotation between it and a cover member later to be described.

The rim or wall 12 has diametrically opposed apertures 14 and 15 substantially midway of its width, such rim or wall having a built-up or thickened portion 16 adjacent the aperture 14 in order to strengthen the rim at this portion and reduce clogging of the material adjacent the aperture. The aperture 14 is tapered and of 20 smaller inner diameter than outer diameter in order to snugly receive a cigarette tube or the like with a cigarette maker.

Within the receptacle a hollow boss forms a housing 17, preferably although not necessarily 25 of substantially cylindrical form, attached to the bottom 11 of the same and has its main bore 18 aligned with the aperture 15 in the rim and a smaller bore 19 in a reduced portion 17' at its opposite end, the apertures or bores 18 and 19 30 being aligned with the bores or apertures 14 and 15 of the rim.

A rod 20 is snugly received within the bore 19 and has an end threaded engaged within a plunger 21 which is received within the bores 35 15 and 18 of the rim and housing. While the bores and the plunger are preferably circular and cylindrical, respectively, it is obvious that they may be of other configuration. Surrounding the rod 20 within the housing 17 is a compression 40 spring 22 which is engaged at one end with the base 21' of the plunger and at its other end with the internal portion of the housing surrounding the rod 20. Near the other end of the rod 20 is a portion 20' of increased diameter which is 45 spaced from its flanged tip 23 by a portion of smaller diameter than the portion 20' and tip 23. The aforementioned portions and tip are snugly and slidably received within the sleeve body 24 of an ejector member 25 having a broadened head 26. The sleeve portion 24 has indentations providing internal projections 27 adapted to engage the flange 23 of the rod and prevent withdrawal of the rod past the indentations. A compression spring 28 is positioned within the 50 sleeve, having its ends compressed by contact

with the end of the rod 20 adjacent the flanged portion of the rod 23 and with the end internal wall 25' of the ejector. Thus the head 26 is resiliently mounted on the rod 20. The end of the enlarged portion 20' nearer the tip 23 contacts the indentations 27 when the rod extends into the ejector a predetermined amount in order to limit compression of the relatively weak spring 28.

A cover member 29 is provided for the receptacle and includes a top wall 30 and a rim or cylindrical side wall 31, adapted to snugly and rotatably receive the upstanding rim or wall 12 of the container 10. The rim 31 is provided with diametrically opposite apertures 32 and 33 which may be aligned with the apertures 14 and 15 of the receptacle rim 12 when the cover is in proper position. A flange or boss 32', 33' is provided adjacent the apertures 32 and 33, respectively, and on the outer portion of the rim to facilitate the reception of a pipe bowl adjacent the apertures and the extended flange 13 of the receptacle member. Similarly, a slightly raised boss is provided on the outer portion of the rim 12 of the receptacle 10 adjacent the aperture 14 in order to provide a snugger engagement with the rim of the cover member at this location, and thus to effectively seal the cover from leakage through the aperture 14 of the container.

If desired, the bottom 11 and top 30 of the receptacle and cover may be respectively concave and convex in order for the receptacle to more readily conform to the shape of the body when carried.

While the device may be readily constructed of plastic material, for certain advantages including resistance to corrosion and the like, the invention is not restricted to manufacture from any particular material.

In the operation of the device the receptacle 10, with the cover removed, may be filled with the fluent material to be dispensed and the plunger and ejector moved to a position within the confines of the rim or wall 12 by manual manipulation permitting the cover to be placed on the receptacle. If the apertures 14 and 15 of the receptacle are entirely out of registration with the apertures 32 and 33 of the cover, the material will be confined within the receptacle to the exclusion of air, light and the elements. As such, the receptacle may be carried on the person or kept for a substantial time without the contents being adversely affected.

To dispense material from the receptacle the rim and top of the cover 29 are grasped in one hand and the flanged portion 13 of the receptacle in the other and the receptacle rotated relative to the cover until the apertures of the cover and receptacle are in registration. If desired, the bottom 11 of the receptacle may carry markings indicating the position of the apertures 14 and 15 in the rim 12 although this is not necessary. Upon the apertures of the receptacle and cover registering the plunger 21 is forced through the aperture 15 of the receptacle and the aperture 32 or 33 of the cover which is in registration by the spring 22 which tends to normally bias the plunger to this position. The pipe or other device which it is desired to fill is then placed beneath the aperture 14 of the receptacle and the registering aperture of the cover and the device tilted so that the registering discharge apertures are at a lower level than the remainder of the device. In this position the material within the container will gravitate toward the discharge

openings and into the space between the ejector head 26 and the discharge apertures. Depression of the plunger 21 then moves the rod 20 and ejector 25 through the space toward the discharge apertures to force the material therethrough which does not fall out by gravity. The plunger may be operated as many times as necessary to eject the desired amount and accompanied by shaking of the container in order to carry the material to the lower portion of the container for discharge. A pipe may be placed directly beneath the discharge apertures, as shown in Fig. 2, in which position the head 26 may tamp the material into the pipe.

During filling of the pipe the ejector head may extend down into the pipe, as shown in phantom lines in Fig. 2, to lightly tamp the tobacco. After the last downward stroke of the plunger 21 projecting from the device may be used as a tamp to more firmly pack the tobacco in the pipe.

At the completion of discharge the device may be closed manually by grasping the cover with the thumb and middle finger over the diametrically opposed apertures and pressing the plunger and ejector inwardly, the other hand grasping the flanged portion 13' of the receptacle and rotating it until the apertures of the cover and receptacle are out of registration. Similarly, the thumb and middle finger may be placed over the apertures when the receptacle is being rotated to open position such that upon the apertures registering, the plunger and ejector may be felt.

It will be obvious to those skilled in the art that various changes may be made in the embodiment of the invention described without departing from the spirit and scope thereof and therefore this invention is not limited by that which is shown in the drawings or described in the specification but only as indicated in the appended claims.

What is claimed is:

1. A combination container and dispenser for fluent material comprising a relatively flat cylindrical open top receptacle having a bottom and a rim, the bottom having a flange with a gripping portion extending substantially beyond the rim, the rim having diametrically opposite apertures spaced substantially midway of the rim sides, a housing within the receptacle having a main and a reduced bore aligned with said apertures, a rod snugly received by said reduced bore, a cylindrical plunger received by said main bore and the rim aperture in communication therewith, the rod extending within the plunger and threadedly engaged therewith, a compression spring on said rod within said housing tending to hold a portion of said plunger extended from said housing, said rod having a flanged tip on its remote end and a portion of increased diameter spaced therefrom by a portion of smaller diameter, an ejector member having a mushroom head and a sleeve body slidably receiving said remote end and said increased diameter portion and said smaller diameter portion, the sleeve body having internal projections spaced from the head for engaging said tip and said increased diameter portion and preventing complete withdrawal of said rod therefrom and limiting the inward movement of said rod thereinto, a compression spring within said sleeve body between said head and the tip 75 of said rod for normally biasing said ejector

member outwardly from said rod to the extent permitted by said projections, and a cover for said receptacle having a top and a rim snugly and rotatably receiving the rim of said receptacle, the rim of said cover having diametrically spaced apertures adapted to be aligned with those of the receptacle to permit discharge of fluent material and projection of said plunger for manipulation.

2. A combination container and dispenser for fluent material comprising a relatively flat cylindrical open top receptacle having a bottom and a rim, the bottom having a flange with a gripping portion extending substantially beyond the rim, the rim having diametrically opposite apertures, a housing within the receptacle having a main and a reduced bore alignable with and communicable with said apertures, a rod snugly received by said reduced bore, means on said rod for limiting its movement into the housing, a cylindrical plunger received by said main bore and the rim aperture in communication therewith, the rod extending within the plunger and threadedly engaged therewith, a spring within said housing tending to hold a portion of said plunger extended from said housing, said rod having a flanged tip on its remote end and a portion of increased diameter spaced therefrom by a portion of smaller diameter, an ejector member having a mushroom head and a sleeve body slidably receiving said remote end and said increased diameter portion and said smaller diameter portion, the sleeve body having internal projections spaced from the head for engaging said tip and said increased diameter portion and preventing complete withdrawal of said rod therefrom and limiting the inward movement of said rod thereto, a compression spring within said sleeve body between said head and the tip of said rod for normally biasing said ejector member outwardly from said rod to the extent permitted by said projections, and a cover for said receptacle having a top and a rim snugly and rotatably receiving the rim of said receptacle, the rim of said cover having diametrically spaced apertures adapted to be aligned with those of the receptacle to permit discharge of fluent material and projection of said plunger for manipulation.

3. A combination container and dispenser for fluent material comprising a relatively flat cylindrical open top receptacle having a bottom and a rim, the rim having diametrically opposite apertures, a housing within the receptacle alignable with both of said apertures and in communication with one of said apertures, a rod snugly received within said housing, means for limiting movement of said rod within the housing, a plunger received by said housing, the rod extending within the plunger and engaged therewith, means within said housing tending to hold a portion of said plunger extended from said housing, an ejector member having a sleeve body receiving said rod, the sleeve body having means for engaging said rod and preventing complete withdrawal of said rod therefrom, means within said sleeve body for normally biasing said ejector member outwardly from said rod to the extent permitted by said withdrawal preventing means, and a cover for said receptacle having a top and a rim snugly and rotatably receiving the rim of said receptacle, said cover rim having diametrically spaced apertures adapted to be aligned with those of the receptacle to permit

discharge of fluent material and projection of said plunger for manipulation.

4. A combination container and dispenser for fluent material comprising a relatively flat cylindrical open top receptacle having a bottom and a rim, the rim having diametrically opposite apertures, a housing within the receptacle in alignment with said apertures and in communication with one of said apertures, a rod snugly received within said housing, a plunger received by said housing, the rod engaging the plunger, means tending to hold a portion of said plunger extended from said housing, an ejector member slidably associated with said rod, means for preventing disengagement of said rod and said ejector member, means for normally biasing said ejector member toward disengagement from said rod to the extent permitted, and a cover for said receptacle having a top and a rim snugly and rotatably receiving the rim of said receptacle, said cover rim having spaced apertures adapted to be aligned with those of the receptacle to permit discharge of fluent material and projection of said plunger for manipulation.

5. A combination container and dispenser for fluent material comprising a relatively flat cylindrical receptacle having a bottom and a rim, the rim having at least two spaced apertures, a housing within the receptacle, in alignment with said apertures, a rod snugly received within said housing, a plunger received by said housing, the rod engaging the plunger, means tending to hold a portion of said plunger extended from said housing, an ejector member slidably associated with said rod, means for preventing disengagement of said rod and said ejector member, means for normally biasing said ejector member toward disengagement from said rod to the extent permitted, and a cover for said receptacle having a top and a rim snugly and rotatably receiving the rim of said receptacle, said cover rim having spaced apertures adapted to be aligned with those of the receptacle to permit discharge of fluent material and projection of said plunger for manipulation.

6. A combination container and dispenser for fluent material comprising an open top receptacle having a bottom and a rim, the rim having at least two spaced apertures, a rod slidably positioned within said receptacle and received by one of said apertures, means tending to eject said rod from said receptacle through one of said apertures, means limiting the ejection of said rod therefrom, an ejector member slidably associated with said rod, means for preventing disengagement of said rod and said ejector member, means for normally biasing said ejector member outwardly from said rod to the extent permitted, and a cover for said receptacle having a top and a rim snugly and movably receiving the rim of said receptacle, said cover rim having spaced apertures registerable with those of the receptacle to permit discharge of fluent material and projection of said rod for manipulation.

7. A tobacco container and dispenser comprising a pair of cup members each comprising a cylindrical wall and a closure for such wall at one end of the same, said cup members being fitted together to form a relatively tight container with the cylindrical wall of one cup member rotatably engaging the cylindrical wall of the other cup member, said cup members having circumferentially spaced apertures capable of being brought into alignment, a reciprocating member

mounted in the inner cup member in a manner that when the apertures are in alignment said reciprocating member will project through the aligned apertures at one location on the circumference and permit the discharge of tobacco through the aligned apertures at the other location on the circumference of the cups, said reciprocating member being movable to serve as a tamper for tobacco in a smoker's pipe.

8. In a tobacco container and dispenser including a pair of cup members each comprising a cylindrical wall and a closure for such wall at one end of the same, said cup members being fitted together to form a relatively tight container with the cylindrical wall of one cup member rotatably engaging the cylindrical wall of the other cup member, said cup members having diametrically opposed apertures capable of being brought into alignment, and a compressible member reciprocably mounted in the inner cup member in a manner that when the apertures are in alignment said reciprocable member will

project through the aligned apertures at one end of the diameter and permit the discharge of tobacco through the aligned apertures at the opposite side of the cup, that improvement which consists in providing a raised portion immediately surrounding the inner cup member discharge aperture for contacting the interior of the cylindrical wall of the outer cup member to provide a substantially air-tight seal.

MAX FRIEDMAN.
